UNITED STATES PATENT OFFICE.

HOWARD GREER, JR., OF CHICAGO, ILLINOIS.

COKE-DRAWING MACHINE.

977,522.

Specification of Letters Patent. Patented Dec. 6, 1910.

Application filed September 7, 1904. Serial No. 223,585.

To all whom it may concern:

Be it known that I, HOWARD GREER, Jr., a citizen of the United States, residing at Chicago, county of Cook, and State of Illinois, have invented certain new and useful Improvements in Coke-Drawing Machines, of which the following is a full, clear, and exact specification.

This invention relates to that class of machines for drawing coke from coke ovens which usually comprise a hoe or rake carried upon a horizontally arranged reciprocal handle which in turn is pivotally mounted upon a car or truck upon vertical and horizontal axes so that while being inserted into or withdrawn from the oven it may be raised or lowered or laterally deflected to suit the situation of the coke within the oven, the coke drawn out by the hoe falling upon a suitable conveyor which is also mounted on the truck and by it is cast up in a pile out of the way.

When the hoe is drawn through the coke, the particles being drawn out by the hoe shape themselves into a pile of approximately pyramidal form with the apex turned in the direction of the line of movement. This pyramid grows less and less acute as the hoe advances and also decreases in depth or in the direction of its vertical axis, the hoe and inner particles of the pile slipping past the particles at the sides or perimeter which are left behind in two straight rows at both edges of the hoe, and if the movement be carried far enough, the hoe will eventually pass by practically all of the particles formerly constituting the pile.

This invention is designed to obviate the described defect in the operation of the hoe and therefore has for one of its important objects to change the plane of the hoe with relation to its line of bodily travel so that it will approximate a right angle with the side of the pile, alternately on opposite sides and hence alternately throw the sides of the pile inwardly toward the line of general advance and thereby keep the particles advancing in front of the hoe, this action of the hoe being also capable of being utilized for the further purpose of working the hoe into the crevices of the coke when being embedded preparatory to drawing the coke.

The walls of coke ovens being comparatively thick and the doors comparatively narrow, it is obvious that in order to reach

all parts of the coke bed with the hoe the handle thereof must be laterally deflected throughout a considerable range and if the center of deflection be any considerable distance outside the door, the truck must be shifted backward or forward to allow the handle to pass the inner edge of the door. The invention therefore has for its further object to so improve the machine as to avoid this obvious and serious objection of having to shift the car with changes of angle of the hoe handle.

In embedding the hoe into the coke it frequently happens that it engages at a point where the coke is solid, and even though it should enter a crevice between the masses, the crevice is so irregular as to render it difficult to embed the hoe by direct downward movement and hence it is desirable to also vibrate the hoe back and forth to effect an entrance; and the invention therefore has for its further object to give the hoe such vibratory motion.

With the described ends in view the invention consists in certain features of novelty in the construction, combination and arrangement of parts whereby the said objects and certain other objects which will hereinafter appear are attained, all as fully described with reference to the accompanying drawings and more particularly pointed out in the claims.

In said drawings Figure 1 is a plan view partly broken away and showing the wall of the oven in section. Fig. 1^a is an enlarged detail section of the hoe tilting mechanism. Fig. 2 is a side elevation of the machine with the parts in position shown in Fig. 1, the wall of the oven being in vertical section. Fig. 3 is an enlarged vertical, longitudinal, sectional view of the hoe and a part of its handle and operating mechanism. Fig. 4 is a transverse section thereof on the line 4—4 Fig. 3. Fig. 5 is a horizontal section thereof on the line 5—5 Fig. 4. Fig. 6 is a transverse section on the line 6—6 Fig. 5. Fig. 7 is a vertical, longitudinal sectional view of the machine partly broken away showing the hoe withdrawn and elevated ready to be inserted. Fig. 8 is an enlarged transverse section on the line 8—8 Fig. 7. Fig. 9 is a plan view of the truck partly broken away, with the superstructure removed. Fig. 10 is a rear elevation thereof partly broken away

and partly sectioned. Fig. 11 is an enlarged plan view partly in section of the clutches and connected parts for operating the various mechanisms as hereinafter described.

5 Fig. 12 is a detail rear elevation of the clutch mechanism for raising and lowering the hoe handle, and Fig. 13 is a vertical section on line 13—13 Fig. 2.

1 I is the wall of the coke oven having the usual doors through which the coke is drawn and one of which is shown at 2, and 3 is the track or railway passing along the side of the oven contiguous to these doors and on which the aforesaid truck for supporting 10 the drawing machine is driven from door to door at will, usually by a suitable motor mounted upon the truck. In this exemplification of the invention one pair of truck wheels has its axle 5 provided with clutch 6 and bevel gear connection 7 with a worm wheel shaft 8 which is driven by worm 9 on the shaft of a suitable motor 10, the latter being disconnected from the shaft 5 when desired by shifting the clutch 6 as will be 15 understood. The conveyer for receiving the coke as it is drawn from the door 2 and casting it up on the pile at a suitable distance from the machine, as before described, may be of any suitable construction. It is 20 shown as being composed of slats 11 secured to two endless chains 12, 13 which pass around sprocket wheels 14, 15 on a shaft 16 at one end of the conveyer, and this shaft is mounted in suitable bearings 17 and has a 25 sprocket and chain connection 18 with the shaft 8 through the intermediary of a clutch 19 capable of throwing the conveyer into or out of action as desired. The upper end of the conveyer is supported by an idle shaft 30 35 mounted in the upper end of a curved frame or boom 21 whose lower end is pivoted on a rod 22 which is mounted in suitable brackets 23 on the frame 24 of the truck so that the outer end of the conveyer 40 45 may be raised and lowered and in order that the outer end may be thus adjusted when required and may be adequately supported while in use, the frame or boom 21 is connected near its upper end to a stay rod 25, 50 one on each side, whose lower ends are attached by any suitable connections 26 to two uprights 27 respectively which are rigidly secured to the sides of the boom 21 respectively at their lower ends and have adjustable connection at their upper ends with the frame 24 of the truck. These adjustable connections consist of eyebolts 28 pivoted to the frame 24 and passing through lugs 29 secured to the uprights 27 respectively 55 60 and provided with nuts 30 on opposite sides of the lugs whereby the uprights 27 may be drawn toward the frame 24 pulling on the stay rods 25, for raising the conveyer.

65 The frame 24 of the truck is preferably quadrant shape in plan view so as to better

accommodate the concentric guides 31 for the auxiliary carriage or slide 32 which rests upon the truck frame 24 and is provided with flanges 33 or other suitable means for engaging with the guides 31 and holding 70 the carriage or slide 32 in position, the carriage or slide 32 being curved or of quadrant shape similar to the frame 24 as better shown in Fig. 1. The curvature of both of these members is outward or away from the 75 wall of the oven, with the lower end of the conveyer central with relation to the ways or guides 31 and projecting toward the oven wall considerably beyond the inner edge of the carriage or slide 32, as better shown in 80 Fig. 1, so that as the coke is withdrawn from the door 2 it may be readily directed upon the lower end of the conveyer by any suitable chute 34 secured to the truck frame 24, and which frame has an opening or passage 35 in its under side for the accommodation of the said conveyer and the coke supported thereon. All of the operating mechanism, with the exception of the conveyer and means for driving the truck, is mounted 85 upon this auxiliary carriage or slide 32 and is capable of having its position on the truck readily changed throughout the length of the ways 31 in order to introduce the hoe into the oven at various angles with relation 90 to the oven walls as will now be explained.

95 Formed on or secured to the slide 32 are two frame members 35, 36 and in these is journaled a horizontal shaft 37 upon which is pivoted a tilting frame 38, constituting 100 the support for the hoe and its handle and provided with two pairs of flanged rollers 39, 40 pivoted therein on pins 41 and serving for the direct support of the handle of the hoe which may be constructed in any suitable way but which is shown as composed of two channel bars 42, 43 arranged with their hollow sides together as better shown in Fig. 8, and fitted accurately between the flanges of the two pairs of rollers 39, 40, 105 the pairs of rollers being situated in the frame 38 a considerable distance apart, as shown in Figs. 2 and 7, so that the handle of the hoe will be given an adequate support while it will be free to slide or run between the rollers without liability of bending when the hoe, 44, carried on the inner end thereof meets an obstruction. The frame 24 of the truck is provided with a segment rack 45 arranged on the upper side thereof 110 concentrically with the ways 31 and in a pair of hangers 46, see Figs. 9, 10, on the under side of the slide 32 is journaled a worm shaft 47 which meshes with the said segment rack 45 and when rotated, it will be 115 seen, causes the slide or auxiliary carriage 32 to travel back and forth along the ways 31 independently of any movement of the truck on the rails 3. The center of the arcs on which the ways 31 are struck being situ- 120 125 130

ated somewhere within the door 2 of the oven or very close to the wall of the oven it will be seen that this bodily revolving movement of the carriage or slide 32 provides for 5 the introduction of the hoe at various angles and to substantially all points within the oven walls, without shifting the truck on the track 3 or causing the hoe to discharge the contents of the oven where it will not 10 find proper lodgment upon the conveyer, whereas if the center of horizontal oscillation of the hoe handle were situated over the truck or at any considerable distance from the outer face of the wall, the range 15 of deflection of such handle, without moving or shifting the truck on the track, would be materially limited.

The necessary motion is imparted to the worm 47 by any suitable operative connection 20 with a motor 48 preferably mounted directly upon and moving with the slide 32. This operative connection may consist, for example, of two trains of gears, one of which comprises gears 49, 50, 51 and 52 25 transmitting motion to a shaft 53 on which is secured a pinion 54 meshing with an idler 55 which engages a pinion 56 on the shaft 57 of the worm 47. The other train of gears comprises gears 58, 59 and 60 which also 30 transmit motion to the shaft 53. The gears 49 and 58 are arranged on the motor shaft 63, the gears 51 and 59 on the shaft 37, and the gears 52 and 60 on the shaft 53, but all 35 these gears are loose on their respective shafts and are connected thereto only through the intermediary of independent clutches so that motion may be imparted to the shaft 53 by either train independently of the other, and because of the presence 40 of the idler gear 50 in one of these trains, one train rotates the shaft 53 in a direction opposite that of the other, it being observed that gears 58 and 59 intermesh directly whereas gears 49 and 51 have the idler 50 45 interposed between them. Consequently when one train of gears is active the worm 47 moves the auxiliary carriage or slide 32 in one direction on the ways 31 and when the other train is rendered active it moves the 50 carriage or slide in the opposite direction, thereby rotating the hoe on its vertical axis with the center of said rotation at the center of the arc on which the curved ways 31 are described and it will be understood that the 55 wider this arc the further into the oven such center will be situated, although it is not essential for obtaining some of the advantages of thus bodily revolving the auxiliary slide or carriage, that the center of revolution be actually within either the door or the oven proper, the principle being that by thus revolving the carriage or slide 32, the center may be carried much closer to the oven and as close as may be necessary in 60 order to enable the hoe to clear the inner

corners of the doorway when the hoe is introduced at an oblique angle for reaching the sides of the oven near the front.

All of the gears 51, 59, 52, 60 are loose on their respective shafts 37, 53 and they are 70 preferably formed on or secured to and in fact constitute one member of their respective clutches before referred to. These clutches are similar in construction, and in Fig. 11 the clutches which drive the gears 51, 75 59 are illustrated in section as typical of all of them. It will be seen by reference to this figure that the gear wheel is hollow or the toothed portion being formed on an annular flange 62 which surrounds a cone 64. 80 This cone, together with the gear, constitutes one member of the clutch, the other member of which is in the form of a cup 65 secured to the shaft on which the gear is loosely journaled so as to slide longitudinally but revolve therewith. In each of the shafts is formed two slots 66 and through the hubs of the cups 65 pass keys 67, 68 and these keys are connected together in such a way that when one of the cups 65 at one 90 end of the shaft is thrown into engagement the cup 65 on the opposite end of the same shaft will be thrown out of engagement. In order to do this the shaft is made hollow and in it is situated a sliding rod 69 to 95 which the said keys are connected as shown in section in Fig. 11 in connection with the shaft 37, the construction for the shaft 53 and keys 68 being similar and the rod corresponding to rod 69 being shown at 70, Fig. 100 11. In order that the requisite longitudinal movement may be imparted to the rods 69, 70, they are provided with operating handles or levers 71, 72 respectively which have suitable connection with the rods, consisting of 105 a screw 73 screw threaded in a cap 74 and provided with swivel connection 75 with the end of the rod. This construction in connection with the rod 69 is shown in section in Fig. 11, and the construction is similar 110 for the rod 70 and lever 72.

When the lever 71, for example, is oscillated the screw 73 will pull the rod 69 longitudinally or force it inwardly according to the direction of oscillation, and thereby 115 throw one of the clutch members 65 out of action and the other one into action. The one that is in action will rotate the gear wheel 51 or 59 and thereby impart rotation to the gear wheel 52 or 60 on that side. If 120 now it should be desired to shift the auxiliary carriage or slide 32 longitudinally of the ways 31, the clutch lever 72 will be thrown to the right or to the left according to the direction in which it is desired to send the carriage. If for example it be thrown to the right, as viewed in Fig. 11, the lever 71 having previously been thrown to the right, the shaft 53 will become connected to 125 the train of gears 51, 52 and the worm 47 130

will be rotated accordingly. Should it be desired to move the carriage 32 in the opposite direction the lever 71 will be thrown to the left and the lever 72 correspondingly moved, thus connecting the gears 59, 60 with their clutch members 65 and thereby imparting rotation to the gear 47 through the gear 60 and shaft 53 in the opposite direction to that in which it was rotated by the train 51, 52, etc. - On the other hand should it be desired to allow the carriage 32 to remain at rest but to move the hoe handle 42, 43, up, or down, the lever 72 would be so placed as to allow both clutch members 65 on the shaft 53 to remain out of engagement whereby one or the other of the gears 52, 60 may be utilized as an idler for communicating rotation to either of a pair of gears 76, 77, which are journaled loosely upon a shaft 78 and are provided with clutch members 79, 80 respectively adapted to be engaged alternately by companion clutch members 81, 82 sliding on shaft 78 but operatively connected therewith by keys 83, 84 respectively so that the shaft 78 will rotate to the right or to the left accordingly as the clutch member 81 or the member 82 is in engagement with its companion member. The clutch members 81, 82 are secured through the medium of the keys 83, 84 to a rod 85 inserted through shaft 78 like the rods 69, 70, and the end of rod 85 is connected to an operating lever 86 like the levers 71, 72 and by a means similar to that described with reference to the lever 71, namely, the screw 73, cap 74 and coupling 75. The shaft 78 is provided with a screw 87 on which is arranged a nut 88 secured to a slide 89 which takes its support upon the top of the carriage 32, thus relieving the screw 87 of transverse strain. The slide 89 is pivoted to the lower end of a forked link 90 whose upper end is pivoted to a horizontal or substantially horizontal lever 91. One end of the latter is pivoted at 92 in a suitable standard or fixed support 93 mounted on the carriage or slide 32 and the other end of the lever 91 is connected to the pivoted frame 38, which constitutes a guide and keeper for the hoe handle, through the medium of any suitable connection such as a pair of hangers 94 connected by a cross bar 95 on which is arranged a lug 96 pivoted to lever 91. By this means it will be seen that when the nut 88 travels along the screw 87, as a result of the rotation of the latter, the lever 91 will be raised and lowered and as a consequence the inclination of the hoe handle will be changed, the handle being lowered at the outer end when the nut 88 moves toward the clutch 81 and raised when the nut moves in the opposite direction and this action of the nut is under the control of the operator through the handle or lever 86 which gives the nut an operative connection with the motor 48 through either train of gears 49, 50, 51, 52 and 76 which moves the nut in one direction, or 58, 59, 60 and 77 which moves the nut in the opposite direction the length of the screw 87 or as long as the proper one of the clutches 81, 82 is held in engagement with its companion clutch member. The lever 91 is preferably composed of flexible material such as tempered steel so that in the event of this vertical oscillation of the hoe handle meeting with an abnormal resistance, the lever 91 will yield without damaging the mechanism.

The means for inserting and withdrawing the hoe, that is moving its handle longitudinally through its guide rollers 39, 40 will now be described. The channel bar 43 is formed on the under side with a series of teeth 97 constituting a rack bar and with this rack bar engages a pinion 98 keyed to shaft 37 and consequently is adapted to be rotated to the right or to the left accordingly as the clutch lever 71 is thrown in one direction or the other and hence the hoe handle will be moved longitudinally the full length of the rack bar 97, or as long as one of the clutches on the shaft 37 is in engagement, this action also being under the absolute control of the operator through the medium of the lever 71.

The hoe proper 44 has pivotal connection with its handle on vertical and horizontal transverse axes, one of these axes is constituted by a pin 99, arranged horizontally and extending transversely of the hoe handle, and connects the hoe to a shank 100, which is arranged between and pivoted to a pair of lugs 101 on the back of the hoe, the shank 100 being provided at its lower end with laterally elongated bearings 102, for the pin 99. The shank 100 is pivoted in a yoke 103 by means of a vertical pin 104, which constitutes the other one of the axes of the hoe. The yoke 103 is formed on or secured to an arm 105 which is attached in any suitable manner to the channel bars 42, 43 constituting the handle of the hoe. The shank 100 is provided with two arms 106 arranged parallel with each other and projecting inwardly along the arm 105 and between these arms 106 is situated an eccentric cam 107, whose periphery is cylindrical and so formed as to remain parallel with the inner faces of the arms 106 and continually contact therewith during the lateral oscillation of the arms 106 on the pivot 104 and which oscillation is caused by the rotation of the cam 107 between the arms 106. The cam 107 is mounted upon one end of a shaft 108, journaled contiguous to the cam in bearings 109, 110 which are formed on or secured to the upper side of the arm 105, and the shaft 108 is also supported in bearings 111 located at suitable intervals throughout the length of the lower channel bar 43. It will thus be seen that when the shaft 108 is rotated

the hoe will be oscillated on its vertical axis 104 or given the movement before referred to necessary for preventing the particles of the coke or other material from slipping 5 past the hoe, or vice versa, while the hoe is being withdrawn, as well as giving the hoe that wriggling movement which facilitates its introduction in a downward direction in the coke bed. Rotation for this purpose may 10 be imparted to the shaft 108 by any suitable means but preferably by a small motor 112 mounted directly upon the hoe handle and preferably at the outer end of the hoe handle so as to at the same time serve as a 15 counterbalance for the handle and hoe, the outer end of the shaft 108 being provided with a gear wheel 113, with which meshes a pinion 114 on the shaft of the motor 112. Electrical connection is established with the 20 motor 112 from any suitable source of current through a flexible connection 115, which is preferably wound up by any suitable take-up device 116 of a well known form for winding up tapes, etc., mounted upon and 25 moving with the slide 32, so that the motor will have its independent connection during its travel back and forth and without depending upon the medium of any metallic parts of the machine for that purpose or 30 making such connection through the intermediary of any parts that have been inserted into the oven.

The pivot 99 permits the hoe 44 to be folded backwardly under its handle while 35 being inserted and after it is inserted it may be pulled downwardly into its operative position by a rod 117 pivoted at 117^a to the upper end of the hoe proper and arranged in suitable guides along the top of channel 40 bar 42. This rod 117 is sufficiently flexible to allow the hoe to make its various described movements without interference, and it may be given longitudinal movement by a pin wheel 118 journaled in the frame 38 45 on a shaft 119, one of whose bearings 120 is eccentric thereto and is provided with a handle 120^a whereby the pins of wheel 118 may be thrown downwardly into engagement with holes 122 in the rod 117. The 50 shaft 119 may be rotated by handle 121 and thus cause the hoe to vibrate on its pivot 99. The cam 107 is incased as far as possible by an extension 123 of the upper side of channel bar 42, which is slotted at 124 for 55 the passage of the rod 117, the arm 105 being provided with side flanges 105^a.

In order to relieve the strain on the pivots 99, 104 as far as possible when the hoe is in operation, the upper end of the hoe is 60 turned backwardly, as shown more clearly in Fig. 7, and provided with a socket 125 which fits over the upper end of pivot 104 and the upper end of yoke 103 when the hoe is thrown downwardly, as shown in Fig. 2.

65 With a machine thus constructed it will

be seen that the operator has absolute control over all movements of the hoe which are independent of one another and any part of the oven may be reached by the hoe without shifting the truck on the track, by 70 simply manipulating the two levers 71, 86 which imparts rotation to the worm 47 and causes the carriage 32 to travel back and forth on the truck independently thereof, the worm 47, if desired, being movable 75 longitudinally of its shaft 57 and springs 126, 127 being interposed between the ends of the worm and one of the hangers 46 and the pinion 56 respectively so that should the hoe handle or hoe meet with an abnormal resistance or obstruction during the 80 travel of the carriage 32 upon the ways 31, the springs 126, 127 will yield sufficiently to give the operator an opportunity to throw the lever 72 and stop the movement of the 85 carriage 32. It will also be seen that during the withdrawing movement of the hoe which is effected by the pinion 98 and rack bar 97, the hoe is also given the important wriggling movement or oscillation on its 90 vertical axis for purposes before described as long as the motor on the hoe handle is left in operation, and this too is under the absolute control of the operator.

Having thus described my invention what 95 I claim as new therein and desire to secure by Letters Patent, is:

1. In a machine for the purpose described the combination of a hoe handle and a hoe pivoted thereto on a vertical axis, means for 100 supporting the handle horizontally and means for oscillating the hoe on the said axis.

2. In a machine for the purpose described the combination of a hoe pivoted on a vertical axis contiguous thereto, means for moving 105 the hoe horizontally and means for oscillating the hoe on said axis.

3. In a machine for the purpose described the combination of a hoe rotatable on a vertical axis and a handle therefor rotatable 110 about a different vertical axis, means for supporting the handle and means for oscillating the hoe about the first said axis.

4. In a machine for the purpose described the combination of a hoe rotatable on a 115 vertical axis, a movable handle therefor rotatable about a different vertical axis, means for supporting the handle and means mounted upon and movable with the handle for oscillating the hoe about the first said axis.

5. In a machine for the purpose described the combination of a hoe, a handle therefor, a bifurcated arm secured to the hoe and pivoted to said handle, a cam journaled on 120 the handle and arranged between the branches of said arm and means for rotating said cam and thereby oscillating the hoe.

6. In a machine for the purpose described, the combination of a hoe handle, a hoe piv- 125

- oted thereto on a horizontal axis, positive means for operating the hoe, the upper edge of said hoe beyond the pivot being deflected rearwardly, and means other than the operating means for engaging said top projection for bracing and forming a rigid lock for the hoe.
7. In a machine for the purpose described the combination of a hoe handle, a hoe pivoted on a horizontal axis and connected thereto, an operating connection with the hoe extending toward the opposite end of the handle and having perforations, an eccentric pin wheel having pins adapted to engage in said perforations and means for turning said wheel.
8. In a machine for the purpose described the combination of a hoe, a handle for said hoe comprising two channel bars secured with their hollow sides together and having pivotal connection with the hoe, a shaft journaled within said channel bars and extending lengthwise thereof, an operative connection between the shaft and the hoe whereby the latter is oscillated upon its pivot and means for rotating said shaft.
9. In a machine for the purpose described the combination of a hoe handle, a hoe having pivotal support on one end thereof, a motor mounted on the other end of said handle, an operative connection between the motor and hoe for moving the hoe on its pivot, and means for pivotally supporting the handle on a horizontal axis.
10. In a machine for the purpose described the combination of a hoe handle, a hoe having pivotal support on one end thereof, a motor mounted on the other end of the handle, an operative connection between the hoe and the motor whereby the hoe is moved on its pivot, means for supporting and moving the handle longitudinally, a flexible connection between the motor and a source of power, and means for taking up the slack in said flexible connection as the motor moves with the handle.
11. In a machine for the purpose described, the combination of a hoe, an independently movable truck, a reciprocating handle for the hoe supported for movement on an imaginary vertical axis outside the truck, and means supported on the truck for reciprocating the handle.
12. In a machine for the purpose described, the combination of a hoe, a handle therefor, means for supporting the handle for movement on an imaginary normally vertical axis within the oven door when the hoe is inserted, and means for moving said support.
13. In a machine for the purpose described the combination of a hoe, a handle therefor, a curved way, a support for said handle on said way and yielding means for moving said support back and forth along said way.
14. In a machine for the purpose described the combination of a hoe, a handle therefor, a curved way, a support for said handle mounted on said way, a motor mounted on said support, a segment on said support, a worm engaging the segment, two trains of gears between the worms and motor for rotating the worm in either direction, and means for disconnecting either train at will.
15. In a machine for the purpose described, the combination of a hoe, a handle therefor, a truck, a curved way on said truck, the imaginary axis of said way being situated at a point beyond the vertical plane of the oven wall when the hoe is inserted in the oven, a carriage mounted on said way and on which said hoe handle is mounted and movable longitudinally independently of said carriage.
16. In a machine for the purpose described the combination of a hoe, a handle therefor, means for pivotally supporting said handle, a screw, means for rotating the same at will, a traveling nut on said screw, and a link connecting said nut with the first said means.
17. In a machine for the purpose described the combination of a hoe, a handle therefor, means for pivotally supporting said handle, a screw, means for rotating the same at will, a traveling nut on said screw and a yielding operative connection between said nut and the first said means.
18. In a machine for the purpose described the combination of a hoe, a handle therefor, means for pivotally supporting said handle, a screw, means for rotating the same at will, a traveling nut on said screw, a pivoted lever connected with the first said means and a link connecting said nut and lever whereby the movement of the nut will oscillate the lever.
19. In a machine for the purpose described the combination of a hoe, a handle therefor, a carriage movable along an indirect line, means for pivotally supporting said handle on said carriage on a horizontal axis, a driving means for moving said carriage, a reciprocating means for moving said handle longitudinally, a tilting means for tilting the handle, a motor, two trains of gears connecting said driving, reciprocating, and tilting means with said motor, one of said trains being a reversing train, and means for rendering either train active at will.
20. In a machine for the purpose described the combination of a hoe, a handle therefor, a carriage movable along an indirect line, means for pivotally supporting said handle on said carriage on a horizontal axis, a driving means for moving said carriage, a reciprocating means for moving the handle longitudinally, a tilting means for tilting the handle, a motor, two trains of gears connecting said driving, reciprocating, and tilting means, with said motor, one of

- said trains being a reversing train, shafts on which said gears are loosely mounted in pairs, and two clutches for each of said pairs adapted to alternately connect the 5 gears of that pair with their said shaft.
21. In a machine for the purpose described the combination of a truck, a conveyor having one end mounted thereon extending beyond the front of the truck, and 10 comprising a frame pivoted to the truck, uprights rising from said frame, adjusting screws connecting said uprights with the truck, and independent stay rods secured to said uprights and to the outer end of said 15 frame for adjustably supporting the conveyor.
22. In a machine for the purpose described, the combination of a hoe, a handle to which said hoe is connected on a horizontal pivot, 20 a support, means for connecting the handle to the support on a normally vertical imaginary pivot within the oven door, and means for moving the support.
23. In a coke drawer, the combination of a 25 truck and a bodily movable carriage mounted thereon arranged to travel laterally through the arc of a circle and provided with a reciprocating ram.
24. In a coke drawer, the combination of a 30 truck, a laterally movable bodily traveling carriage thereon provided with a reciprocating ram, and means embodying a curvilinear trackway for positioning the carriage and ram at varying angles with relation to the 35 truck.
25. In a coke drawer, the combination of a truck and a bodily movable carriage mounted thereon arranged to travel laterally through the arc of a circle and provided 40 with a reciprocating ram, and means for locating the ram carriage at varying positions on the truck.
26. A coke drawer comprising a truck provided with a curved controlling track- 45 way, and a laterally movable ram carriage and ram supported upon the truck and controlled solely by said trackway as to their relative position with relation to the truck.
27. In a coke drawer, the combination of a 50 truck and a bodily movable carriage mounted thereon arranged to travel laterally through the arc of a circle and provided with a reciprocating ram, means for locating the ram carriage at varying positions on the 55 truck, and means for actuating the ram.
28. A coke drawer comprising a truck provided with a curved trackway described from a theoretical center outside the truck, and a carriage mounted on the truck having 60 devices engaging said trackway and provided with a reciprocating ram.
29. In a coke drawer, the combination of a truck having a flat upper surface and a curved trackway, and an unattached freely 65 movable carriage mounted for lateral move- ment on the truck and controlled as to its movement solely by said trackway, and provided with a reciprocating ram.
30. In a coke drawer, the combination of a supporting truck provided with a curved 70 trackway extending transversely across the truck, a carriage freely mounted upon said truck and adapted to be controlled as to its position by said trackway, and a reciprocating ram mounted in said carriage. 75
31. In a coke drawer, the combination of a truck, a laterally movable ram carriage, a reciprocating ram mounted on said carriage, and means mounted on and traveling with the ram carriage for actuating the ram at its 80 various positions with relation to the truck.
32. In a coke drawing machine arranged to travel in front of and closely adjacent to a bank of ovens: the combination with the truck, of a ram carriage having a reciprocating ram and arranged to travel laterally 85 in the arc of a circle described from a theoretical center so positioned with relation to the operative position of the oven door as to permit of varying lateral positions of the 90 ram to explore the interior of the oven without moving the truck.
33. In a coke drawer, the combination of a truck provided with a curvilinear track- 95 way, and a non-pivotaly-attached ram car- 95 riage controlled as to its direction of travel by said trackway and provided with a reciprocating ram.
34. In a coke drawer, the combination with a bank of ovens and supporting rails 100 located in front thereof, of a laterally trav- eling truck mounted on the rails, a freely and bodily movable ram carriage mounted on the truck and provided with a reciprocating ram, and means for operating the ram 105 carriage and ram and for defining their movement with relation to an imaginary center adjacent to the oven door, for the purpose described.
35. A coke drawing machine consisting of 110 a portable truck provided with a shifting relatively movable ram carriage and ram, and means embodying a curvilinear track- way for independently adjusting the ram carriage and ram and for locating them at 115 varying angles and positions with relation to the truck.
36. A coke drawing machine consisting of a portable truck provided with a shifting relatively movable ram carriage and ram, 120 means embodying a curvilinear trackway for independently adjusting the ram carriage and ram and for locating them at varying angles and positions with relation to the truck, and means mounted on the ram car- 125 riage for actuating the ram.

HOWARD GREER, JR.
